UNITED STATES PATENT OFFICE.

GEORGE BULLOCK, OF GRAND JUNCTION, COLORADO.

PARCEL-CARRIER.

1,167,628.

Specification of Letters Patent.

Patented Jan. 11, 1916.

Application filed June 27, 1914. Serial No. 847,596.

To all whom it may concern:

Be it known that I, GEORGE BULLOCK, a citizen of the United States, residing at the city of Grand Junction, county of Mesa, and State of Colorado, have invented a new and useful Parcel-Carrier, of which the following is a specification.

This invention relates to a device for carrying various kinds of parcels or objects.

10 In the embodiment in which I have chosen to illustrate the features of my present invention there is a combined handle and strap or band holding-member formed in a single piece and comprising a handle part in such 15 position to the remaining portions of the device that it may be readily engaged manually, and strap or band retaining-means in connection with said handle whereby a number 20 of straps or bands may be held in position upon the parcels or objects to be carried.

While I have chosen to illustrate the handle in integral connection with the strap or band retaining parts it will be obvious that 25 the connection may be otherwise effected, so that it will be understood that in illustrating and describing the preferred embodiment or form of the invention, I do not restrict myself to identical features nor do I 30 exclude from the scope of my invention, as set forth in the appended claims, such variations and modifications in the construction and arrangement of parts as constitute equivalent structures.

35 One object of the invention is to provide a device for carrying parcels and the like comprising a number of straps or bands adapted to be secured around the parcels or objects, in combination with a handle supported at a suitable distance from the parcel being carried, so that the handle may be 40 readily engaged manually, and provided with means whereby the straps or bands permanently engage the handle so as to hold the handle in connection with the parcel. This 45 construction involves the elimination of a special base to which the ends of the handle are secured, since there is at each end of the handle a device for engaging with a strap or band so that the usual base is unnecessary.

Other objects and advantages of the invention will be apparent from the following description, reference being made to the accompanying drawing in which I have illustrated the construction and some of the uses

of the preferred form of the invention, and in which—

Figure 1 is a top or plan view of the handle and strap engaging means in connection therewith. Fig. 2 is a side elevation partially in section illustrating the structure and formation of the device when the handle is composed of sheet metal. Fig. 3 is a perspective view of the device applied to use for carrying a number of volumes, the straps 60 passing around the superposed volumes in different directions to prevent slipping thereof. Fig. 4 is a perspective view of the device in connection with a roll of fabric, such as a blanket, and illustrating two 65 straps passing around the roll, the third strap, employed in connection with the separate objects as illustrated in Fig. 3, being unnecessary in the latter instance.

When the handle is composed of a single 70 piece of sheet metal in connection with the strap engaging portions at the opposite ends thereof, said integral structure includes a handle member 1 having its side edges bent or pressed to provide upturned rounded side 75 portions so as to provide an elongated handle portion which is rounded or arcuate in cross section. It will be understood that the rounded surface of the handle thus formed is at the under side against which the hand 80 is engaged. The two ends of the handle portion 1 are curved downwardly so that the handle, viewed in side elevation, is substantially 85 in the form of an arch. Each end of the handle includes a flat portion 2, the side portions 2 being in the same, or substantially the same, plane and being of such area that the straps may pass thereover and engage therewith so as to hold the handle in 90 connection with the parcel.

95 In the embodiment shown the device is formed from a sheet metal blank in which the base portions 2 are integral with the handle 1 and in each of said base portions there are formed two parallel slots 3 adapted to receive the straps 4 which pass around the parcel transversely of the handle. This arrangement permanently holds the straps 4 in connection with the base portions 2 and prevents the handle from becoming disconnected or detached from the parcels. In carrying objects or articles of the type illustrated in Fig. 4, for instance, only two straps 100 or bands are necessary and these encircle the object in the manner shown. In carrying 105 110

numbers of separate objects or articles, such for instance, as books, it is preferable to employ the two straps 4 which pass around the article transversely of the plane of the handle and also to employ an additional strap 5 which passes around the articles transversely of the straps 4 and parallel with the plane of the handle, in order to prevent any of the articles from becoming separated.

In order to hold the strap 5 in its proper position and to engage said strap with the handle, I have provided a slot 6, adjacent to each of the base portions 2, through which the strap 5 may be passed, as illustrated in Figs. 1 and 2. The strap 5, passing through the slots 6, may extend over the straps 4 and between the up-turned projections 7 at the outer ends of the base portions 2. The projections, being at each side of the strap 5, will prevent lateral movement of said strap at the outer extremities of the base portions 2, thereby holding the different parts in proper relative adjustment.

It will be understood that when the strap 5 is not needed, as for instance in carrying articles of the type illustrated in Fig. 4, said strap may be detached or withdrawn and may be replaced at will, or whenever separable objects are to be carried.

It will be understood that I do not restrict myself to specific features other than as set forth in the appended claims.

35 I claim:

1. A device of the character described, comprising a handle portion, a downwardly curved portion at each end of said handle portion provided with a horizontal transverse slot adapted to receive a strap passing therethrough longitudinally under said handle, and an outwardly extending base portion integral with each of said curved portions below said slots and the longitudinal strap passing therethrough.

2. A device of the character described, comprising a handle portion, a downwardly curved portion at each end of said handle portion, each of said curved portions being provided with a horizontal slot adapted to receive a strap passing therethrough longitudinally under said handle, a base portion extending outwardly from each of said curved portions below said slots and provided with parallel slots adapted to receive a strap passing transversely over said base portions.

3. A device of the character described, comprising a sheet metal section including two base portions at the ends thereof having slots for straps, an integral handle rising from said base portions and having its

side edges curved to form a rounded under surface, and means whereby a strap may be retained in position on said base portions 65 longitudinally under said handle.

4. A device of the character described, comprising a section of sheet metal having two base portions at the ends thereof provided with parallel slots arranged to receive straps passing transversely of said base portions, said section of sheet metal being bent to form a handle rising from said base portions and having slots therein adjacent to said base portions arranged to 75 receive a strap passing through said slots and longitudinally under said handle, and upwardly curved edge portions on said handle forming a rounded under surface.

5. A device of the character described, comprising a section of sheet metal bent to form two base portions at the ends of said section in substantially the same plane and to form a handle rising from said base portions, the side edges of said handle being bent to provide a rounded under surface for said handle, means for holding straps passing transversely of said base portions at the ends of said handle, and means for holding a strap passing longitudinally 90 of said base portions under said handle.

6. A parcel carrier comprising a handle composed of sheet metal having upwardly bent side edges forming a rounded under surface and the ends of said handle being 95 extended downwardly, flat base portions integral with the extended portions of said handle and having slots arranged to receive straps passing transversely over said base portions and having slots arranged to receive a strap passing longitudinally over 100 said base portions and under said handle, and upturned projections at the ends of said base portions for the purpose described.

7. A parcel carrier, comprising a handle 105 composed of sheet metal having upwardly bent side edges forming a rounded under surface and a depressed upper surface, the ends of said handle being bent downwardly, flat base portions integral with the downwardly bent portions of said handle and each having a transverse slot arranged to receive a strap passing longitudinally over 110 said base portions and under said handle, and means for preventing lateral movement 115 of the strap with respect to said base portions.

In witness whereof, I have signed this specification in the presence of two subscribing witnesses.

GEORGE BULLOCK.
